PICKER STICK LINKAGE

George H. Hufferd, Shaker Heights, Ohio, assignor to Houdaille-Hershey Corporation, Detroit, Mich., a corporation of Michigan

Application July 27, 1948, Serial No. 40,894

5 Claims. (Cl. 139—149)

1

This invention relates to an improved loom construction, and particularly to an improved linkage for controlling the movements of the picker stick of a fly shuttle type loom.

As is well known, the movement of the picker sticks of a loom is one of the most critical factors entering into the successful operation of the loom at high speed. In all loom constructions wherein a picker is rigidly secured to the top end of the picker stick, it is essential that the path of movement of the shuttle-engaging portions of the picker define a substantially straight line, generally parallel to the path of movement of the shuttle along the lay.

In my copending application Serial No. 37,951, filed July 9, 1948, there is described and claimed a unique control linkage for a picker stick embodying the supporting of the picker stick entirely from a primary bracket which is secured to the end of the rock shaft which is commonly found on all looms. The control linkage constituted a pair of links which had their opposite ends respectively secured to spaced pivot bearings provided on the primary bracket and on a secondary bracket which is adapted for rigid securing to the lower portion of the picker stick. Specifically, the construction of my above identified pending application involved a lower link of substantial length which was generally horizontally disposed and hence imparted primarily a lateral positioning control upon the picker stick throughout the normal range of movement of the stick. The other link was relatively short in length and was pivotally secured in depending relationship to a pivot bearing on the primary bracket which was substantially laterally displaced from the end of the rock shaft. While such an arrangement has been found to be very effective in controlling the movements of the picker stick to provide the required straight line path for the shuttle engaging portions of the picker, some difficulties were presented in obtaining the necessary clearance for the various moving parts and particularly, in providing sufficient space for the connection of a hydraulic check unit to operate between the primary and secondary brackets to check both the shuttle throwing and the shuttle catching movements of the picker stick. Furthermore, the essential geometry of the linkage involved symmetrical displacements of the short link on either side of its vertical position.

Accordingly, it is an object of this invention to provide an improved control linkage for the picker stick of a loom of the type employing a pair of links pivotally connecting a picker stick

2

to a primary bracket member secured to the rock shaft and characterized by its avoidance of interferences between the various relatively moving parts.

5 A further object of this invention is to provide an improved control linkage for the picker stick of a loom wherein a plurality of identical links are utilized to effect suitable connection of the picker stick to a primary bracket secured to the rock shaft of the loom, thereby reducing the manufacturing cost of the control linkage by permitting interchangeability of the various links.

10 Still another object of this invention is the provision of a double link support for a picker stick wherein both links pivot only through a very limited range to produce the requisite displacements of the picker stick and furthermore wherein neither link passes a vertical position.

15 The specific nature of the invention, as well as other objects and advantages thereof, will become apparent to those skilled in the art from the following detailed description of the annexed sheets of drawings, which, by way of preferred 20 example only, illustrate two embodiments of the invention.

25 On the drawings:

Figure 1 is a side elevational view of a picker stick control linkage embodying this invention, showing the linkage in assembled relationship to the rock shaft and picker stick of the loom.

Figure 2 is an end elevational view of the linkage of Fig. 1 looking at such linkage from the rock shaft side thereof.

30 Figure 3 is a schematic view showing the various positions assumed by the linkage elements and the picker stick throughout the normal range of movement of the picker stick.

Figure 4 is a view similar to Fig. 3 but illustrating the movements of the picker stick accomplished by a modified form of the invention wherein links of non-uniform length are employed.

As shown on the drawings:

45 Referring to Fig. 1, the numeral 10 indicates a rock shaft of a loom, while the numeral 11 indicates a conventional picker stick. The picker stick 11 is supported for oscillating movements with respect to the rock shaft 10, hence with respect to the lay of the loom (not shown), by a linkage constructed in accordance with this invention, which linkage controls the movement of the picker stick so that the shuttle-engaging portions of a picker (not shown) which is conventionally secured to the top end of the picker

stick, traverses a substantially horizontal straight line path. In general, the linkage comprises a primary bracket 12, rigidly secured to the rock shaft 10, and a secondary bracket 13 which is secured to the lower portion of the picker stick 11 and connected to the primary bracket 12 by a pair of pivoted links 14 and 15. The links 14 and 15 may conveniently comprise either single or double links according to the nature of their pivotal support, but in the particular example illustrated in the drawings, such links are both double links, i. e., they each comprise a pair of identical parallel links for reasons that will be more fully apparent later.

The primary bracket 12 constitutes an integral casting having a split depending portion 12a defining a cylindrical recess to receive the end of rock shaft 10. The split portion 12a is clamped to the rock shaft 10 by a transverse bolt 12d and a transverse tapered key 17. The key 17 is of longitudinally tapering configuration and is drawn into snug engagement with the shaft 10 by a nut 18 threaded upon the threaded end portion of the key. As indicated in Fig. 1, the surface of key 17 which contacts the shaft 10 is of concave configuration to provide a pair of parallel biting edges 17a to increase the securement of engagement of the primary bracket 12 with respect to the rock shaft 10.

In addition, primary bracket 12 defines a pair of vertically spaced pivot bearings 12b and 12c respectively. Both of such bearings are mounted in generally overlying relationship with respect to the end of the rock shaft 10 and it should be particularly noted that the primary bracket 12 does not project laterally beyond the end of rock shaft 10 to any appreciable extent. This arrangement greatly increases the clearance available for the various moving parts of the linkage.

The secondary bracket 13 may also conveniently comprise an integral casting, being of generally U-shape configuration, and has the base portion 13a rigidly secured to the front face of the picker stick 11 in any convenient manner. For example, a plurality of bolts 19 may be provided which pass through a clamping plate 20 engaging the rear face of the picker stick 11 and project through suitable holes in the secondary bracket base 13a to clamp the picker stick 11 between such space and the clamping plate 20.

Each of the arm portions 13b and 13c of the U-shaped secondary bracket 13 are of substantial height and hence project laterally from the picker stick a substantial distance. At the outer end of each of the arm portions, and respectively adjacent the top and bottom parts thereof, a pair of bosses 13d and 13e are provided which respectively define vertically spaced pivot bearings 13f and 13g. As is best shown in Fig. 2, the lateral spacing of the arm portions 13b and 13c of the secondary bracket 13 is sufficient to permit such arm portions to straddle the primary brackets 12 if necessary in one of the extreme positions of the picker stick 11.

With the described arrangement, the upper pair of links 14 are pivotally secured between the upper pivot bearings 12c and 13f while the lower pair of links 15 are pivotally secured between the lower pivot bearings 12b and 13g. The links 14 and 15 are each disposed outwardly of the primary and secondary brackets 12 and 13 and are secured thereto by suitable pivot pins 16.

With the described arrangement, and when the vertical spacing between the primary bracket

5 pivot bearings 12b and 12c is different from the vertical spacing of the pivot bearings 13f and 13g of the secondary brackets, so that the upper links 15 and lower links 14 are non-parallel, it will be found by ordinary design layout procedure, that the dimensions of the links 14 and 15 together with the spacing between the various pivot bearings may be conveniently selected so as to insure that the picker stick 11 will move 10 along a path such that the shuttle-engaging portion of the picker stick will traverse a substantially straight, horizontal line.

The embodiment shown in Figs. 1 and 2 of the drawings is particularly advantageous inasmuch as both the upper links 14 and the lower links 15 are of identical size and hence interchangeable components may be employed. Referring to the schematic diagram of Fig. 3, it is clearly apparent that with the described linkage, the shuttle-engaging portion of the picker stick 11, represented by the end of the short line designated 11a, will follow along a substantially horizontal straight line path when an oscillating movement is imparted to the picker stick 11 in conventional fashion, such as by the usual power lug (not shown). In this schematic diagram, the solid lines represent the intermediate position of the picker stick 11 and the associated linkage, while the dotted lines and the dot dash lines represent the extreme positions assumed by the picker stick.

30 The principles of this invention are not limited to arrangement wherein identical links are employed for the upper and lower links 14 and 15. As is clearly illustrated by the schematic diagram of Fig. 4, unequal length links may also be employed and by a suitable selection of the spacing between the various pivot bearings, this type of linkage will also result in the shuttle-engaging portions of the picker stick 11 moving 35 in a substantially straight line path. In the arrangement of Fig. 4, the upper link 14 is shown as being of somewhat greater length than the lower link 15.

40 In both modifications it should be noted that a relatively small range of pivotal movement of the links 14 and 15 is required to produce the full range of movement of picker stick 11. Furthermore neither link 14 or 15 passes through a vertical position.

45 It should be particularly noted that due to the U-shaped configuration of the secondary bracket 13, and the location of the pivot bearings 13f and 13g in the ends of the arm portions of bracket 13, so that the picker stick 11 is located 50 at a substantially laterally displaced position with respect to the primary bracket 12, plus the fact that the primary bracket 12 does not project laterally any substantial distance beyond the end of the rockshaft 10, an unusually compact unit is achieved in which adequate clearance is provided between the various moving elements of the control linkage. This arrangement therefore finds particular utility in looms 55 wherein it is desired to employ hydraulic check units for checking the shuttle throwing or shuttle catching movements of the picker stick. With the described arrangement, a hydraulic check unit may be conveniently mounted within 60 the space defined between the arm portions 13b and 13c of the secondary bracket 13. It will be observed that such space is substantially free from interference with any of the components of the control linkage throughout the normal 65 range of movement of the picker stick 11.

It will, of course, be understood that various details of construction may be modified through a wide range without departing from the principles of this invention and it is, therefore, not the purpose to limit the patent granted hereon otherwise than necessitated by the scope of the appended claims.

I claim as my invention:

1. A linkage for controlling the movement of a picker stick of a loom comprising a primary bracket adapted for securement to the rock shaft of the loom, said primary bracket defining a pair of vertically spaced pivot bearings overlying the end of said rock shaft, a secondary bracket of generally U-shaped configuration having its base portion adapted for securement to a picker stick and disposed with the arm portions thereof projecting toward said primary bracket, said arm portions of said secondary bracket being sufficiently laterally spaced to straddle said primary bracket, a first pair of aligned pivot bearings respectively formed in the lower part of said arm portion, a second pair of aligned pivot bearings respectively formed in the upper part of said arm portions, a pair of first links pivotally connected between the lower pivot bearing of said primary bracket and said lower pivot bearings of said secondary bracket, and a pair of second links pivotally connected between the upper pivot bearing of said primary bracket and said upper pivot bearings of said secondary bracket, said pairs of links being constructed and arranged to control the movements of said picker stick to shift the shuttle-engaging portion thereof along a substantially straight line path.

2. A linkage for controlling the movement of a picker stick of a loom comprising a primary bracket adapted for securement to the rock shaft of the loom, said primary bracket defining a pair of vertically spaced pivot bearings overlying the end of said rock shaft, a secondary bracket of generally U-shaped configuration having its base portion adapted for securement to a picker stick and disposed with the arm portions thereof projecting toward said primary bracket, said arm portions of said secondary bracket being sufficiently laterally spaced to straddle said primary bracket, a first pair of aligned pivot bearings respectively formed in the lower part of said arm portion, a second pair of aligned pivot bearings respectively formed in the upper part of said arm portions, a pair of links pivotally connected between the lower pivot bearing of said primary bracket and said lower pivot bearings of said secondary bracket, and an additional pair of links identical to the first mentioned pair of links pivotally connected between the upper pivot bearings of said primary bracket and said upper pivot bearings of said secondary bracket, said links and said pivot bearings being proportioned to control the movements of said picker stick to shift the shuttle-engaging portion thereof along a substantially straight line path.

3. A parallel motion picker stick linkage for a shuttle loom comprising a primary bracket defining a pair of generally vertically spaced pivot points, a picker stick bracket arranged interme-

diate the primary bracket and a picker stick, said picker stick bracket defining a pair of generally vertically spaced pivot points substantially laterally displaced from the picker stick, a first link between the uppermost of the pivot points of said primary bracket and said picker stick bracket, said first link being of a length less than the spacing dimension of the pivot points on said primary bracket, and a second link between the lowermost of the pivot points defined by said primary bracket and said picker stick bracket, said second link being of a length equal to the length of said first link, both of said links arranged to preclude pivotal movement thereof through a vertical position.

4. A parallel motion picker stick linkage for a shuttle loom comprising a primary bracket defining a pair of generally vertically spaced pivot points, a picker stick bracket arranged intermediate the primary bracket and a picker stick, said picker stick bracket defining a pair of generally vertically spaced pivot points substantially laterally displaced from the picker stick, a first link between the uppermost of the pivot points of said primary bracket and said picker stick bracket, said first link being of a length less than the spacing dimension of the pivot points on said primary bracket, and a second link between the lowermost of the pivot points defined by said primary bracket and said picker stick bracket, said second link being of a length less than the length of said first link, both of said links arranged to preclude pivotal movement thereof through a vertical position.

5. A parallel motion picker stick linkage for a shuttle loom comprising a primary bracket defining a pair of generally vertically spaced pivot points, a picker stick bracket arranged intermediate the primary bracket and a picker stick, said picker stick bracket defining a pair of generally vertically spaced pivot points substantially laterally displaced from the picker stick, a first link between the uppermost of the pivot points of said primary bracket and said picker stick bracket, said first link being of a length less than the spacing dimension of the pivot points on said primary bracket, and a second link between the lowermost of the pivot points defined by said primary bracket and said picker stick bracket, said second link being of a length less than the spacing dimension of the pivot points on said primary bracket, and a second link between the lowermost of the pivot points defined by said primary bracket and said picker stick bracket, said second link being of a length less than the length of said first link, both of said links arranged to preclude pivotal movement thereof through a vertical position.
